Primary Examiner — Kevin Rudzinski(74) *Attorney, Agent, or Firm* — KPPB LLP(57) **CLAIM**

The ornamental design for a display screen or a portion thereof with graphical user interface, as shown and described.

DESCRIPTION

The FIGURE is a front view of a display screen or portion thereof with graphical user interface showing our new design.

The dot-dash broken lines show the display screen or portion thereof and form no part of the claimed design.

The dot-dot broken lines show portions of the graphical user interface that form no part of the claimed design.

1 Claim, 1 Drawing Sheet# US D775,632 S
